ELECTRICAL REPRODUCING DEVICE

Curtis P. Mitchell, Springdale, Ohio, assignor to
 The Palmer Company, Cincinnati, Ohio, a corporation of Ohio

Application February 12, 1937, Serial No. 125,384

5 Claims. (Cl. 172—239)

This invention relates to electrical apparatus and is particularly directed to an apparatus for electrically reproducing motion at a location different from the location at which it is applied. 5 More specifically, the invention is utilized as an electrically operated system for reproducing, recording, or showing temperatures at points removed from the environment, the temperature of which is being determined. The present invention 10 may be considered in relationship to my previously issued Patent #2,036,091 issued March 31, 1936, disclosing and claiming an electrical reproducing device for the same general purposes and uses as that herein disclosed.

15 It is an object of this invention to provide an apparatus or system for electrically reproducing thermostatically detected temperature changes by means of a unit placed at the environment of temperature change which may be a theatre, an oven, etc., and connected by electrical means to a receiving unit which may be located at a remote point such as the outside of the theatre or the recording room of a bakery or any extremely remote point. The receiving apparatus receives 20 signals from the sending device by electrical control and converts them into mechanical movement which is effective for temperature record 25 or display purposes.

It is a further object of this invention to provide apparatus of this character which is extremely sensitive and which, therefore, transmits the very slightest change in temperature and immediately displays or records the change substantially simultaneously with the occurrence 30 thereof. Moreover, it is arranged that, in the event of power failure, these devices will operate automatically when the power is restored for quickly and accurately reproducing the temperature reading existing at the time of power restoration without requiring manual resetting of the apparatus.

It is a more general object of this invention to provide a system and apparatus for electrically reproducing relative movement at a location remote from the location at which the motion is created and, further, to include the provision of means for effecting the aforesaid electrically reproduced movement in reverse directions as determined by the direction of movement at the 45 source or initially.

It is a still further object of the present invention to provide a system and apparatus of the above character in which synchronizing means is incorporated for maintaining a true operative 50 relationship between the sending and receiving

portions of the apparatus, particularly in the event that the receiving portion of the apparatus becomes inoperative or acts too rapidly or too slowly.

Other objects and certain advantages will be 5 more fully apparent from a description of the accompanying drawing, in which:

The figure of the drawing is a diagram illustrating the electrical and mechanical elements of the apparatus and system and disclosing the 10 electrical connections therebetween.

In the disclosed embodiment of the invention set forth in the above mentioned patent, a series wound commutator type of motor is used. Reversal is accomplished by splitting the field winding into two parts and making the connections so that each field serves for one direction of rotation. The transmitter and receiver portions of the apparatus are kept in synchronism by arranging the circuit so that, as the transmitter advances 15 one step, the voltage in the transmitter is reduced to a point insufficient for its operation by the operation of the receiver, and cannot proceed until the receiver has advanced one step.

The present invention employs small shaded 20 pole induction type motors which have the advantage that they run at uniform speeds. The previous system of synchronizing control is not adapted to the induction type motor since the induction motor is more independent of line voltage. Accordingly, a different system of control 25 and means of synchronizing has been adopted herein.

In order to secure reversal of motion, two induction motors are coupled together and wired to 30 rotate in opposite directions so that energization of the winding of one motor makes it run carrying the other with it, or vice versa. The synchronizing means consists essentially of a rotating contact switch, mounted on the same shaft 35 as the transmitting contact switch, and a similar switch mounted on the same shaft as the receiving contact switch. These switches are connected in such a way (as will be hereinafter explained in detail) that if the receiving portion of the 40 apparatus fails to keep up with, or gets ahead of, the transmitting portion, or does not operate for some reason, the field winding of both motors on the transmitter will be energized at the same time. Since they are wired to run in opposite 45 directions, the transmitter will stop instantly when this occurs. When, and if, the receiving end reaches the proper position, the normal connections are restored on the transmitting motors 50 for operation in one or the other direction.

Referring to the drawing, the sending or transmitting unit is generally indicated at A, and the receiving unit at B. The disclosed embodiment of the invention is arranged for recording temperatures at a point away from the environment, the temperature of which is being determined. For example, the sending or transmitting unit may be located in the interior of a theatre and the receiving unit at the exterior of the theatre, for disclosing to the public the temperature within the theatre. As another example, the sending, or transmitting, unit may be in an oven of a bakery with the recording or receiving unit located in an executive's or manager's office, or in a control room, particularly where the bakery is a large institution.

The thermally sensitive or responsive element of the sending unit is generally indicated at 10. As illustrated, it consists of abutting strips of metal having different coefficients of expansion causing swinging of the strip upon the occurrence of expansion or contraction. It may, however, consist of a Bourdon tube filled with an expandable liquid and carrying an arm which swings back and forth as the tube coils and uncoils due to temperature changes effecting the expandable liquid, as disclosed in the patent heretofore mentioned.

As illustrated, the swinging arm 10 has one end anchored, as at 11. Its swinging end carries a double contact 12 swinging between contacts 13 and 14. The contacts 13 and 14 are in fixed spaced relationship and are mounted on a carrier block 15. The carrier block 15 consists of a nut 16 and arms 17 and 18 projecting laterally from the nut, and carries the respective spaced contacts 13, 14.

The thermally sensitive arm 10 is connected to a source of electrical current through a lead 19. The contacts 13 and 14 are connected to the respective field windings of induction motors 20, 21, by leads 22, 23. The motors 20 and 21 may be a single unit consisting of field windings wired to run in opposite directions. A screw threaded shaft 24 is driven by said motors through reduction gearing, as in the issued patent. Bearings 25 are shown diagrammatically for rotatively mounting said shaft. The nut 16 of the traveling block 15 is traversed by the screw threaded portion of the shaft whereby, upon rotation of the shaft, the block will be moved changing the position of the contacts 13 and 14 with respect to the thermally sensitive member 10.

The shaft 24 carries a rotating contact arm 26 making successive contacts with switch segments or poles 27, 28, 29, and 30. This arm 26 and its contacts constitute the sending switch. The shaft 24 also carries a second contact arm 31, adapted to make successive contact with switch segments or poles 32, 33, 34, and 35. The arm 31 and its contacts constitute the sending switch of the synchronizing system. The contact arm 31 is of such circumferential dimension, or width of contact portion, that with either direction of rotation in passing from one segment or pole to another, it will always reach a new contact segment or pole before the arm 26 reaches a new contact segment, or pole.

Referring to the receiving or recording unit, the receiving motors are indicated at 40 and 41. These motors 40 and 41 are also induction motors having their respective field windings wired to run in opposite directions. The motor shaft 42 of the receiving or recording unit is provided with a screw threaded section 43, traversing an indica-

tor arm 44. This arm 44 carries a recording instrumentality such as a pen or pencil for, drawing a graph line on a record strip 45, being unreeled from a roll 46, rotating at a uniform rate and driven by some means (not shown) and supported in bearings 47, 47. Shaft 42 also carries two rotating diametrically opposite contact arms 48, 49, respectively connected to the field windings of the motors 40 and 41 by leads 50, 51. A supply lead 52 completes the circuits to the respective motors 20, 21, 40, and 41.

The rotating contact arms 48, 49 successively contact segments 53, 54, 55 and 56. These arms 48, 49, and their contacts constitute the receiving switch. Another rotating contact arm 57, is fixed to the shaft 42 and successively contacts switch segments 58, 59, 60, and 61. The arm 57 and its contacts constitute the receiving switch of the synchronizing system. Corresponding stationary contacts of the respective switches, that is, the sending and receiving of the normal system and the sending and receiving of the synchronizing system, are connected by electrical leads 62.

The contact arms 31 and 57 of the respective sending and receiving switches of the synchronizing system are normally out of step 180°. In other words they engage diametrically, opposite contacts of the respective synchronizing switches. Moving contact 57 is connected to the contact 13 of the thermally controlled motor control switch by a lead 63 and moving contact 31 is connected to the other contact 14 of the thermally controlled switch by a lead 66. Thus it is arranged that if the contacts 31 and 57 get into step, both of the sending motors are then in circuit and the respective fields buck each other which results in locking the coupled reversely wound motors against movement in either direction.

Operation

For illustrative purposes, the drawing discloses the system in one of the positions it assumes when at normal rest. As shown, the contact 12 of the thermally sensitive element is out of contact with either contact 13 or 14. Now when there is a temperature change in the environment of the sending apparatus, which may be (for the sake of illustration) a drop in temperature, it may be assumed that the element 10 swings the contact 12 to the right, engaging the contact 13. The current then flows through the field of the motor 20 by way of supply line 19, contact 12, contact 13, lead 22, the motor winding, and supply line 52. This rotates the shaft 24 and tends to move the contact 13 away from the swinging contact 12 until a break is accomplished; that is until the drop in temperature ceases.

Rotation of the shaft 24 by the motor 20 moves the switch arm 26 of the sending switch from contact 28 to contact 29. The current then flows from supply line 19 through arm 26, contact 29, lead 62, contact arm 49, lead 51, the winding of induction motor 41, and supply line 52. This rotates the shaft 43 for moving the recording arm 44 in the appropriate direction to indicate the drop in temperature on the recording sheet.

As soon as the shaft 43 is in rotation, the contact 49 moves from contact 55 to contact 56 which is connected to contact 30 of the sending switch previously dead but now in circuit by virtue of the continued rotation of contact 26 from contact 28 to contact 29. If the drop in temperature continues, the induction motor 20

will continue to run and successive driving impulses will be sent through to the receiver until the contact 13 breaks contact with the swinging contact 12.

- 5 The reverse direction of rotation occurs in the event of a temperature rise, the induction motor 21 then being placed in circuit by way of supply line 19, contact 12, contact 14, lead 23, the winding of the motor, and supply lead 52. In this 10 event, since the shaft 24 is then reversely driven, contact 26 moves to contact 27, the current then flowing from supply line 19 to contact 27, lead 62, contact 53 of the receiving switch, contact arm 48, lead 50, winding of the reverse motor 40, 15 and supply line 52. Then the recording arm 44 moves in the opposite direction to record a temperature rise on the recording sheet.

Synchronization

- 20 The above description of the operation outlines the normal operating sequence of the system, such as continues when the receiving unit keeps in step with the sending unit. It will be noted that the synchronizing switches do not enter into the operation or control of the system as long as 25 the system remains synchronized. In other words, the synchronizing switches are supplemental or secondary devices effective in the circuit only in the event of sluggishness or failure of some sort in the receiving apparatus.

30 To illustrate the operation of the synchronizing switches, it will be presumed that for some reason the receiving unit becomes inoperative due to the failure of the receiving mechanism or the 35 connections thereto. In this case it is highly desirable also to have the transmitter stop, rather than run ahead of the receiver.

When the contact arm 26 moves from contact 28 to contact 29 the contact arm 31 of the sending synchronizing switch moves from contact 35 to contact 32. In fact due to its width, it established this contact with contact 32 before the establishment of contact of arm 26 with contact 29. Assuming the receiver to be inoperative, the 40 contact arm 57 of its synchronizing switch will remain stationary. Now the arm 26 will continue to move along contact 29 while the contact 31 will continue to move along contact 32 until the forward extremity of the arm 31 engages contact 33. Since contact 33 is connected to contact 59, upon which the synchronizing contact arm 57 is resting, this will result in placing the other motor 21 in circuit by way of supply line 52, winding of the motor, lead 66, arm 31, contact 33, lead 62, contact 59, arm 57, lead 65, contact 13, contact 12, and supply lead 19. Thus the windings of the respective induction motors are both in circuit or in a bucking or balanced condition, and the shaft 24 will then remain stationary. Thus the transmitting end will remain inoperative until the receiving end steps up to its proper position and throws the winding 21 out of circuit.

If the receiver is merely slow in acting, it may 45 stop the transmitter, as described above, but, since it finally moves arm 49 from contact 55 to contact 56, and arm 57 from contact 59 to contact 60, the circuit through to contact 33 and arm 57 will be broken, de-energizing induction 50 motor 21 whereupon induction motor 20 may continue to run.

In the event that motor 21 was transmitting a 55 temperature rise and the contact 31 of the synchronizing sending switch was moving in a reverse direction, it will, upon engagement with

contact 33, connect the supply to contact 59 of the receiving synchronizing switch and will thereupon, if the arm 57 has not moved in a normal manner, connect through it and lead 65 to the winding of the induction motor 20 and supply 5 line 52. This results in energizing both motors and results in stoppage of the transmission for the same purpose as in the opposite direction previously described.

It is arranged that the system must keep in step or the coupled induction motors of the sending unit will buck each other and result in a stoppage of the sending impulses.

Having described my invention, I claim:

1. In a reversible motion transmitting and synchronizing apparatus, a pair of induction motors wound for reverse direction of rotation respectively, a pole switch driven by said motors controlling a plurality of controlling circuits, a second electric motor driven switch, the corresponding poles of said motor driven switches respectively in circuit connection, a pilot switch alternately cooperable with oppositely arranged contact elements of said induction motors, a synchronizing switch driven by said induction motors, a second synchronizing switch in driving connection with said second motor driven switch, said synchronizing switches respectively wired for completing the circuit to either one or the other of said induction motors and having their contacts related for energizing the field of the induction motor which is not in operation at the particular time in the event that the second motor driven switch mechanism ceases to operate.

2. In a reversible motion transmitting and synchronizing apparatus, a four pole sending switch, induction sending motors for operating said four pole sending switch, one for each direction of movement, a control switch for controlling said motors, said control switch operated by said 40 motors when the motors are in motion for automatically breaking contact, a four pole receiving switch, induction receiving motors controlled by and actuating said four pole receiving switch, the corresponding poles of the sending and receiving switches electrically connected, said receiving motors wound for reverse directions of movement, means driven by said receiving motors, said four pole receiving switch including diametrically opposite contact arms, each electrically connected for controlling a respective receiving motor, and a synchronizing device, including a switch actuated by the sending motors and a switch actuated by the receiving motors, said latter switches including four poles electrically connected, said latter poles corresponding to those of the sending and receiving switches, said synchronizing switches having their moving contact arms normally substantially 180° out of step and each connected to a respective directional contact of the control switch for placing both sending motors in circuit when moving contacts of the respective synchronizing switches are in step or engaging corresponding contacts.

3. In a reversible motion transmitting and synchronizing apparatus, a sending switch, induction sending motors for operating said sending switch, one for each direction of movement, a switch for controlling said motors, a receiving switch, induction receiving motors controlled by and actuating said receiving switch, said receiving motors wound for reverse directions of movement, means driven by said receiving motors, said receiving switch including a pair of contact arms, each electrically connected for controlling a re- 75

spective receiving motor, and a synchronizing device including a switch actuated by the sending motors and a switch actuated by the receiving motors, said switches electrically connected in the circuit to the sending motors so as to place both sending motors in circuit upon the failure of the receiving motors to operate thereby causing said motors to buck each other and to remain stationary.

10. 4. A reversible motion transmitting and synchronizing apparatus comprising induction motors having reversely wound fields, a pole switch driven by said motors, a pilot switch for energizing and de-energizing the induction motors alternately, a second pole switch, said first mentioned pole switch and said second pole switch having their respective corresponding poles connected electrically, receiving motors controlled by said second pole switch, said motors having oppositely wound fields and said pole switch including a control arm for each field, means driven by said receiving motors and a switch controlling electrical circuit for maintaining said pole switches in synchronism, including switches driven by the respective sets of motors having their contacts electrically connected to the respective induction motors but normally out of circuit, said synchronizing switches adapted to

place that motor in circuit which is not operating when the pilot switch is in connection for causing the respective motors to buck each other when the receiving motors and apparatus fails to function.

5. A reversible motion transmitting and synchronizing apparatus comprising an electrically braked reversible motor driven shaft, a pole switch driven by said shaft, a pilot switch for energizing and de-energizing the motor, a second pole switch, said first mentioned pole switch and said second pole switch having their respective corresponding poles connected electrically, a receiving reversible motor driven shaft controlled by said second pole switch, and said pole switch including a control arm for each direction of motion, means driven by said receiving motor shaft and a switch controlling electrical circuit for maintaining said pole switches in synchronism, including switches driven by the respective motor shafts having their contacts electrically connected to the reversing contacts of the pilot switch but normally out of circuit, said synchronizing switches adapted to place the electrical brake in circuit for locking the first shaft when the receiving apparatus fails to function.

CURTIS P. MITCHELL.
